UNITED STATES PATENT OFFICE.

MICHAEL W. O'BRIEN, OF ROCHESTER, NEW YORK.

BLANK-PRESSING MACHINE.

1,034,493.

Specification of Letters Patent.

Patented Aug. 6, 1912.

Application filed April 15, 1912. Serial No. 691,062.

To all whom it may concern:

Be it known that I, MICHAEL W. O'BRIEN, a citizen of the United States, and resident of Rochester, in the county of Monroe and 5 State of New York, have invented certain new and useful Improvements in Blank-Pressing Machines, of which the following is a specification.

This invention relates particularly to machines for pressing and flattening the leather blanks used for the toplifts of shoe-heels, although the invention is applicable to blank-pressing machines used for various other purposes.

15 The object of the invention is to produce a machine which shall be simple and compact in construction, and at the same time rapid and efficient in operation, and to this end I employ various features of construction which will be pointed out in the following description and claims.

In the accompanying drawings:—Figure 1 is a rear-elevation of a machine embodying the present invention; Fig. 2 is a plan-view, 25 on a larger scale, of the mechanism for imparting intermittent rotation to the die-plate; Fig. 3 is a detail-view, in transverse section, of the movable pressing-member; Fig. 4 is a horizontal section on the line 4—4 30 in Fig. 1; and Fig. 5 is a vertical section on the line 5—5 in Fig. 4, looking from right to left in the latter figure.

The illustrated embodiment of the invention is a machine designed particularly for pressing and flattening top-lifts for shoe-heels. The pressing instrumentalities comprise a lower, flat, stationary member 10, which constitutes also the bed of the machine, and an upper, movable pressing-member 11 in the form of a flat plate. These pressing-members engage the opposite surfaces of the blank or top-lift.

The movable pressing-member 11 is supported by means of two stems 12 fixed in 45 the plate near its ends, these stems sliding vertically through brackets 13 fixed to the bed of the machine. Springs 14 surrounding the stems and engaging, at their respective ends, the heads of the stems and the 50 upper surfaces of the brackets, act to hold the plate 11 normally in raised position. The movement resulting from the action of these springs is limited, however, by means of stop-screws 15 adjustably threaded in the 55 brackets and normally engaging the upper

surface of the plate. By these means the movements of the plate may be adjusted to a minimum sufficient to admit the blanks between the pressing-members, while eliminating unnecessary lost motion.

The movements of the pressing-member 11 toward the fixed pressing-member 10 are produced intermittently by a plunger 16, which slides vertically in a sleeve 17 fixed to the yoke-shaped frame 18 of the machine. 60 The plunger is actuated by a pitman 19 embracing, at its upper end, an eccentric 20. This eccentric is rotated by a horizontal drive-shaft 21. In order that the drive-shaft may be thrown into and out of operation as required, it is provided with a clutch of which one member 22 is splined to the shaft, so that it may slide into and out of engagement with the corresponding clutch-member on a pulley-wheel 29. The pulley 65 normally rotates freely on the shaft, and it may be connected, by a belt, with any suitable source of power. The wheel acts also as a fly-wheel to furnish the momentum necessary to carry the machine smoothly 70 through all portions of its cycle of movements.

The clutch-member 22 is operated by an arm 23 engaging an annular groove in the clutch-member. This arm is loosely pivoted, in turn, upon a shaft 24 which rotates and slides freely in bearings on the frame 18. A spring 25 normally tends to push the arm 23 and the shaft in a direction to engage the clutch-members. At the other end of 85 the shaft, however, is fixed a handle 26 having a hub or boss provided with an inclined face which engages a correspondingly inclined face on the shaft-bearing 27. Accordingly, by turning the handle and the shaft, 90 the inclined surfaces may be caused to move the shaft and the arm 23 horizontally, against the resistance of the spring 25, and thus disengage the clutch-members.

The blanks are introduced between the 100 pressing-members 10 and 11, and removed therefrom, by means of a rotary member in the form of a die-plate 30. This plate is provided with openings 31 of the exact outline which is to be imparted to the top-lifts, the plate thus acting as a die as well as a feeding-member. The die-plate rests upon the surface of the bed 10, and is provided centrally with a boss into which is screwed the lower end of a vertical shaft 32, these 105 110

parts being fixed securely together by a nut 33 also threaded on the shaft. The shaft has a bearing, at its lower end, in the bed 10, as shown in Fig. 5, while its upper portion 5 is journaled in a bracket 33 projecting inwardly from the frame 18.

The shaft 32 is employed to impart intermittent partial rotations to the die-plate, and to this end it is connected with the drive-shaft 21 by means of a mechanism shown 10 particularly in Figs. 1 and 2. On the upper end of the shaft 32 is fixed a star-wheel 34 having radial slots 35 in its lower surface. A stud 36 projects upwardly from the 15 bracket 56, and upon this stud is journaled the hub 53 of an arm 37. The arm carries, near its end, a pin 38 which projects upwardly into position to engage the slots 35 in the star-wheel. A pinion 41 fixed to the 20 upper end of the hub 53 meshes with a pinion 42 fixed to the power-shaft 21. At each rotation of the latter, accordingly, the arm 31 performs a rotation. During one-quarter of this rotation the pin 38 is in engagement with one of the slots 35, so that 25 a quarter-rotation is imparted to the shaft 32 and the die-plate 30. During the remainder of each rotation of the arm 37, however, the star-wheel and the parts connected therewith are locked against rotation by the action 30 of a segmental disk 39 fixed to the hub 53. This disk engages, at this time, one or another of the curved recesses 40 between the arms of the star-wheel, thus acting in the manner of a Geneva stop-mechanism. 35 The parts of the machine are so arranged as to cause the partial rotations of the die-plate to occur while the plunger 16 and the plate 11 are in raised position, while the die-plate dwells during the operation of the 40 pressing-members.

As a convenient means for introducing blanks into the openings 31 of the die-plate the machine is provided with a hopper 43 45 adapted to contain a stack of blanks. This hopper is open at the front, for convenience in introducing the blanks, and it is supported, at its lower end, in a bracket 44, which is fixed to the bed of the machine and overhangs the die-plate so as to bring the hopper directly above the position occupied successively by the openings 31 while the die-plate is at rest. Owing to this arrangement the 50 stack of blanks is supported upon the smooth upper surface of the die-plate during the intermittent movements thereof. Each time the plate comes to rest the lowermost blank descends into one of the openings 31, and on the succeeding partial rotation of the die-plate this blank is carried, in said opening, 55 into position between the pressing-members.

To remove the blanks automatically from the die-plate, after they have been pressed, I employ an ejector comprising an arm 46 60 fixed to a rock-shaft 47. This rock-shaft is

journaled on the base of the machine, and is provided with a second arm 48 connected, by a pitman 49, with an eccentric 51 on the drive-shaft. Accordingly, at each operation of the machine the arm 46 is raised and lowered through an opening in the bed of the machine provided for that purpose, as shown in Fig. 5. The inner end of the arm is provided with a flat head 52 which is thus passed upwardly through one of the openings 31 in the die-plate, thus raising and discharging the blank which has been pressed therein by the last previous movement of the pressing-members. The head 52 is fixed on the arm at such an angle that when it has raised the blank from the die-plate it occupies an inclined position, so that the blank will slide off from it rearwardly and away from the die-plate, thus discharging the blanks at the rear of the machine. 80

The present machine, in addition to condensing and shaping the material of the top-lifts, has the function of flattening the material, which is usually more or less distorted by the operation of punching it. The 90 blanks, when first introduced in the openings 31 in the die-plate, may not lie flat therein, but are liable to project upwardly more or less. Accordingly, to insure the proper introduction of the blanks between the pressing-members, the movable pressing-member or plate 11 is beveled or rounded, on its lower surface, as shown in Fig. 3, at the point where the blanks enter beneath it during the rotation of the die-plate. 95

My invention is not limited to the embodiment thereof hereinbefore described and illustrated in the accompanying drawings, but may be embodied in various other forms within the nature of the invention as it is 100 defined in the following claims.

I claim:—

1. A machine for pressing top-lift blanks having, in combination, a horizontal bed with a flat upper surface constituting a stationary pressing-member, a movable flat pressing-member co-operating therewith, a plunger for moving the latter member toward and from the stationary pressing-member, a drive-shaft journaled horizontally above the plunger and connected therewith by an eccentric mechanism to actuate the plunger, a die-plate rotatively mounted in horizontal position upon the bed and having a portion movable between the pressing-members, the die-plate being provided with a series of openings to receive blanks, a vertical shaft by which the die-plate is actuated, and gearing and stop-mechanism connecting said vertical shaft and said drive-shaft and adapted to impart intermittent partial rotations to the die-plate at the intervals between successive operations of the pressing-members, the openings in the die-plate being spaced to bring 110

one of said openings between the pressing-members and arrest it in that position while the pressing-members are operating.

2. A machine for pressing top-lift blanks having, in combination, a rotary horizontal die-plate provided with a series of blank-receiving openings, means for imparting intermittent partial rotations to the die-plate, upper and lower pressing-members having substantially flat surfaces adapted to engage the upper and lower surfaces of the blanks in said openings, means for imparting operative movements to said pressing-members while the die-plate is stationary, and an 10 ejector for discharging the pressed blanks from the openings in the die-plate, said ejector comprising an arm pivotally mounted in position to engage the lower surface of a blank in one of the openings in the die-plate while the latter is stationary, the 15 ejector having a flat head arranged at an angle so as to cause the blanks so discharged to slide horizontally from the ejector, and mechanism for raising the ejector intermittently during the dwells in the movement 20 of the die-plate.

25

3. A blank-pressing machine having, in combination, upper and lower pressing-members with opposed substantially flat faces, mechanism for moving one of the said members toward and from the other, a die-plate rotatable between said members and perforated with a series of blank-receiving openings forming rigid lateral die-walls, mechanism for imparting intermittent partial rotations to the plate, alternating with the operating movements of the pressing-members, to carry blanks successively to and away from the pressing members, a hopper located in position to discharge blanks into said openings successively before they move into position between the pressing-members, mechanism for discharging the pressed blanks from said openings successively after they leave the pressing-members, and power-mechanism for actuating all of said mechanisms in timed co-operation.
